John F. Rathbone, Albany, N.Y.

Letter Patent of Design No 1191 dated 10th July 1846, antedated
20th April 1847

The Schedule referred to in these Letters Patent and making
part of the same.

To all whom it may concern:

Be it known that I, John F. Rathbone of Albany, in the
County of Albany, and State of New York, have invented or produced
a new design for an ornamental Bay stove, and I do hereby declare that
the following is a full clear and exact description of the same, -

reference being had to the accompanying drawings making part of this specification in which Fig 1 represents a prospective view of a stove after my design - Fig. 2 represents the side of my stove upon a larger scale, the figures upon ^{both} sides, as also upon the ends, being respectively alike. The panel *ccc* is filled with a composition of fruits, flowers, foliage &c as represented - The figures, shown at *kk* & *ii* are continued entirely around the panel, forming a border thereof. The outer border *m m m* is also carried around the panel. The figures shown at *n n*. Fig. 3^d is formed by two cornucopiae with foliage & the panel *o o*, Fig. 3 is filled with a cornucopiae fruits, flowers, foliage &c. The borders as indicated are the same as upon the sides -

What I claim as my invention and desire to secure by Letters Patent is the combination of ornamental figures herein shown and described, forming an ornamental design for a stove.

Attest,

John F. Hathbone,

Eric J. C. Kennedy,

W. W. Chas. C. Miles
